UNITED STATES PATENT OFFICE.

LUCY A. SHRADER, OF ELMIRA, NEW YORK.

RAILWAY RAIL-SUPPORT AND RAIL-FASTENER.

1,114,543.

Specification of Letters Patent.

Patented Oct. 20, 1914.

Application filed October 6, 1913. Serial No. 793,696.

To all whom it may concern:

Be it known that I, LUCY A. SHRADER, a citizen of the United States, residing at Elmira, in the county of Chemung and State of New York, have invented certain new and useful Improvements in Railway Rail-Supports and Rail-Fasteners, of which the following is a specification.

This invention relates to improvements in railway rail supports and fasteners, and has for one of its objects to provide a device whereby rails are supported throughout their entire length both from vertical and lateral movement and displacement and whereby the opposite rails are firmly united and supported and prevented from "creeping" or other movements either laterally or longitudinally of the roadbed.

Another object of the invention is to provide a device whereby rails are supported equally throughout their entire length so that all jars and unevenness of motion are obviated under the impact of the rolling stock.

With these and other objects in view the invention consists in certain novel features of construction as hereinafter shown and described and then specifically pointed out in the claims, and in the drawings illustrative of the preferred embodiment of the invention.

Figure 1 is a plan view of a portion of a railway track including the rails, rail supports and ties. Fig. 2 is a side elevation partly in section, of the parts shown in Fig. 1. Fig. 3 is an enlarged side view, partly in section, of a portion of the improved device. Fig. 4 is a transverse section on the line 4—4 of Fig. 3. Fig. 5 is a perspective view from beneath, of one of the rail supporting members at one side. Fig. 6 is an enlarged perspective view from above of the part shown in Fig. 5. Fig. 7 is an enlarged perspective view from above, of the opposite end of one of the rail supporting members. Fig. 8 is an enlarged perspective view of one of the rail holding members.

Corresponding and like parts are referred to in the following description and indicated in all the views of the drawings by the same reference characters.

The improved device includes a support for each rail corresponding in length thereto with the confronting ends of the rails located intermediate the ends of the supports, while the confronting ends of the

supports are located intermediate the ends of the rails. The supports are arranged to bear beneath the whole length of the rail and likewise against the edges of the flanges so that the rails are supported from both vertical and lateral movement throughout their whole lengths. The supports are likewise firmly attached to the rails at their ends and the supports are further reinforced by devices located between the roadbed and the supports with fastening devices extending into the roadbed material.

The rails are represented conventionally at 10 and of the usual form and length, about 30 feet. The rail supports are in the form of channeled bars comprising the base portion 11 which engages beneath the flanges of the rails and vertical webs 12 which bear against the edges of the rail flanges, as represented in Fig. 4. The central portions of the rail supports are located beneath the joints between the confronting ends of the rails, while the ends of the supports are located midway between the ends of the rails, as represented in Figs. 1 and 2. The rails are connected to the web 12 near the joints of the rails by clamp bolts or other suitable fastening devices 13. Located beneath the rail supports at the joints between the confronting ends of the rails are blocks 14 preferably of stone or like material which are embedded in the roadbed material, and preferably supported by the tamping which is forced around and beneath the blocks in the usual manner. The rail supports of each of the rails are connected near the joints of the rails by transverse members 15 which are reduced where they pass beneath the supporting members, whereby bracing shoulders 16 are produced to bear against the confronting faces of the rail supports. The members 15 may be located at any distance from the joints of the rails, but will generally be placed about 14 inches from the terminals of the rails and at each side of the supporting members 14. Forced into the roadbed at the points where the reduced portions of the members 15 are located are relatively heavy rods or posts 17 with the upper ends of the rods extending through the members 15 and bearing beneath the rail supports and provided with threaded bores in their upper end to receive clamp members 18, the latter extending through the base portion 11 of the rail support and with flaring heads

19 which engage in countersunk apertures in the base of the rail 10. By this means the rail supports are firmly anchored to the supporting posts or rods 17, while the members 15 are likewise firmly attached to the rail supports, the flaring heads 19 extending upwardly, as shown in Figs. 3 and 4 into cavities in the bottoms of the flanges of the rails, to assist in holding the parts. 10 The blocks 14 and the rods 17 are thus located at the joints at the terminals of the rails, and the rail supporting members are further supported between each set of the rods 17 and the supports 14 by ties 20 of any 15 suitable construction. For the purpose of illustration wood ties are shown, but it will be understood that ties of any suitable construction may be employed.

At their confronting ends the rail supports are provided with interlapping joints constructed as represented in Figs. 5, 6 and 7. At one end each of the rail supports is reduced to form longitudinal projections 21 at each side which correspond in thickness 25 to the base portion 11 of the support and correspond in width to the webs 12, as represented in Fig. 7. Extending from the base 11 of the rail support midway between the projections 21, is a thinner projection 30 22. At its opposite end each of the rail supports is reduced, as represented at 23, to receive the projections 21 of the adjacent support and likewise provided with a longitudinal cavity 24 to receive the relatively 35 thin projection 22 of the adjacent support, the material of the support between the reduced portions 23 and the cavity 24 forming rib-like portions 25 which engage respectively between the projections 21 and 22.

By this means the confronting ends of the 40 rail supports are formed with overlapping joints which firmly unite the parts and effectually prevent displacement both vertically and laterally. The supporting members 14 may also be located at other points 45 beneath the rail supports, as for instance as shown in Figs. 1 and 2 beneath the joint of the rail supports, and the stone supports may likewise be located at other points, as preferred, without departing from the principle of the invention or sacrificing any of its advantages.

Having thus described the invention, what is claimed is:

1. Railway rail supports spaced apart 55 and abutting end to end, tie members extending beneath said supports, members having internally threaded sockets and disposed beneath said tie members, and threaded members engaging said sockets and having heads seated in said rail supports.

2. Railway rail supports spaced apart and abutting end to end, tie members extending beneath said supports, members having internally threaded sockets and disposed beneath said tie members, and threaded members engaging said sockets and having heads seated in said rail supports, the upper ends of said heads extending above the rail supports and adapted to engage rail-way rails when the same are disposed upon said supports.

In testimony whereof I affix my signature in presence of two witnesses.

LUCY A. SHRADER.
